UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

TRAVERSE-MOTION FOR YARN-SPINNING APPARATUS.

1,076,910.

Specification of Letters Patent.

Patented Oct. 28, 1913.

Application filed January 6, 1913. Serial No. 740,329.

To all whom it may concern:

Be it known that I, ALONZO E. RHOADES, a citizen of the United States, and resident of Hopedale, county of Worcester, State of Massachusetts, have invented an Improvement in Traverse-Motions for Yarn-Spinning Apparatus, of which the following description, in connection with the accompanying drawing, is a specification, like characters on the drawing representing like parts.

This invention relates to apparatus for controlling the reciprocation of the ring-rail in a yarn-spinning frame in such manner that the yarn is first wound upon the bobbin to form a primary winding or bunch, and thereafter a secondary or service winding is laid to complete the building of the yarn-mass upon the bobbin.

As is well known the primary winding or bunch is utilized in the loom to bring into action, through the instrumentality of a feeler, mechanism which will effect automatically a change or replenishment of filling in the working shuttle when the filling therein has been exhausted to a predetermined extent, the bunch containing a sufficient length of yarn to preserve continuity of filling when filling replenishment is effected.

In my present invention the primary winding or bunch is formed with a short traverse but at a relatively high speed, so that the yarn is laid at quite a steep pitch or angle, giving an open or cross-wound effect and with a reduced amount of yarn compared with the compact or solid wind imparted by a slower traverse.

The amount of yarn laid in the bunch or primary winding is regulated automatically, and when such winding is completed the traverse is changed or shifted to complete the winding with a long traverse and at a much slower rate of speed, so that the principal portion of the yarn-mass is built up in a compact and solid manner.

It is not broadly new to provide a traverse motion which operates to provide at first a short, quick traverse and thereafter a long, slow traverse, but in my present invention I have provided various novel features of construction whereby the operation of the apparatus is improved as a whole.

The novel features of my invention will be fully described in the subjoined speci-

fication and particularly pointed out in the following claims.

In the present embodiment of my invention the ring-rail rises and falls with the rise and fall of the oscillating member or arm of the builder-motion, and the chain or flexible connection between the winding mechanism of the builder-motion and the ring-rail is let off gradually to effect the gain of the traverse, during both the primary and the secondary or main windings. There is no increase in the length of the traverse, however, during either winding, the only change being the single shift from short traverse to long traverse at the completion of the primary winding.

Figure 1 is a front elevation of a portion of a spinning frame with a traverse motion applied thereto embodying my present invention, the parts being shown as positioned for effecting the short, quick traverse of the ring-rail; Fig. 2 is a vertical sectional view taken on the line 2—2, Fig. 1, looking toward the right, showing the two cams for effecting respectively, the short traverse for the preliminary winding, and the long traverse for the main winding, of yarn upon a yarn-receiver or bobbin; Fig. 3 is a view principally in plan of the major portion of the traverse motion shown in Figs. 1 and 2, a few of the parts being in horizontal section substantially on the line 3—3, Fig. 1, one of the transverse girths of the frame being broken out to show parts below it; Fig. 4 is a detail view in front elevation of a portion of the mechanism for controlling automatically the change or shift from short to long traverse, the disk-like member of such mechanism being omitted for the sake of clearness of illustration though it is indicated by a dotted circle; Fig. 5 is a left hand side elevation, and part section, of the traverse shifting mechanism, the section being taken on the line 5—5, Fig. 1, looking toward the right; Fig. 6 is a detail to be referred to of a part of the means for effecting the gradual rotation of the drum of the winding mechanism.

The spindle-rail 1 provided with usual rotatable spindles for the yarn-receivers or bobbins 2, the vertically-reciprocating ring-rail 3 provided with rings 4, the lifter-rods, as 5, Fig. 1, and the co-operating rocker partly shown at 6, may be and are all of well known construction.

In practice there are a series of lifter-
rods and rockers, the latter being connected
to rock in unison and weighted to elevate
the rail, and connected with the set of rock-
ers is a flexible connection or chain 7 which
5 passes over the guide-sheave 8 to the drum
of the winding mechanism forming a part
of the builder-motion. The spindle-rail 1
and longitudinal girder 9 are rigidly se-
cured to the end frame 10 of usual construc-
10 tion and forming no part of my invention,
the sheave 8 being mounted on a bracket 11
secured to a cross-girth 12 bolted to the
girders 9, one at each side of the frame.

15 A hanger 13 depends from the girth 12
and supports the inner end of a horizontal
shaft 14, supported at its outer end by a
bracket 15 attached to the end frame 10, said
shaft constituting a fulcrum for the oscil-
20 lating arm of the builder-motion, said arm
being best shown in Fig. 3 as comprising
parallel and frontwardly extended branches
16, 17 of unequal length, rigidly connected
by a cross brace 18 and by the long hub 19,
25 the latter rocking on the fulcrum shaft 14
between the hanger 13 and a positioning
collar 20.

The usual winding mechanism is mounted
30 on the longer branch 17 and comprises the
drum 21 and attached gear 22, rotatably
mounted on the lateral stud 23, and the
worm 24 in mesh with and to rotate the
drum gear to let off the chain 7, said worm
35 being fast on the pick-shaft 25 mounted to
rotate in suitable bearings 26 on the branch
17, the pick-shaft having fast upon its front
end the ratchet or pick-wheel 27 rotated step
by step by the pawl 28. This pawl is mount-
40 ed on the pawl-carrier 29 adapted to rock
on the pick-shaft, and the pawl-carrier is
actuated by or through the rod 30 extended
upward therefrom and passing loosely
45 through a guide 31 on the girder 9. Said
rod has vertically spaced collars 32 fixed
thereon, to receive between them the hook-
like front end 33 of an arm 34 fixedly se-
cured at its rear end on a transverse rock-
50 shaft 35 mounted in suitable bearings 36,
Fig. 2, on the branches of the builder-arm.
45

55 The open hook 33, see Fig. 6, is of such
shape that the rocking movement of the arm
34 will reciprocate vertically the rod 30
without any cramping or binding thereof,
and it should be noted that the feed stroke
55 of the pick-pawl 28 is effected by the rise
of the rod 30, and positively, as will be ex-
plained, the weight of the arm 34 and its ad-
juncts being amply sufficient to depress the
said rod and effect thereby the retractive
60 stroke of the pawl.

Referring to Fig. 1 the branches 16 and
17 of the builder-arm are provided respec-
tively with roller or other studs 37, 38 which
serve as followers for the builder or trav-
65 erse cams, for herein I employ two cams,

one to control and actuate the builder-mo-
tion during the formation of the primary
winding or bunch, and the other to actuate
the builder-motion during the formation of
the secondary or main winding. The cam
70 shaft 39, rotated by usual and suitable
mechanism, not shown, is mounted in bearing
stands 40, 41 respectively carried by the
end frame 10 and the cross-girth 12, the
main traverse-cam 42, shown in Fig. 2 as a
75 four-point traverse-cam of familiar form,
being mounted rotatably on the shaft 39 and
cooperating with the follower 38, see Fig. 1.
When said cam 42 is effecting the oscillation
of the builder-arm the long traverse is im-
80 parted to the ring-rail, and at such time the
cam is clutched to the shaft 39 to rotate
therewith, but during the formation of the
primary winding the cam is unclutched from
the shaft and remains at rest and in-
85 active. A second traverse-cam 43 is mount-
ed to rotate with the shaft 39 and is also
movable axially thereof into and out of op-
erative engagement with the follower 37, the
connection between the cam and shaft being
90 effected in any suitable manner, as by a key
and slot connection 44, see dotted lines Fig.
2. Said cam 43 has a large number of short
peripheral cam portions, as shown in Fig.
95 2, of such shape as to act through the inter-
vening connections and effect the short trav-
erse of the ring-rail to lay the yarn in
building the primary winding or bunch,
the cam portions cooperating with the fol-
lower 37 to impart a series of short and
100 rapid oscillations to the builder-arm. This
results in laying the yarn in the primary
winding at quite a steep pitch or angle, giv-
ing an open or cross wound effect which re-
duces the actual amount of yarn in the
105 bunch without materially reducing the size
of the bunch.

Referring to Fig. 1 it will be seen that the
traverse-cams 42, 43 are located side by side
and between the branches of the builder-
arm, and said cams are separated laterally
during the primary winding sufficiently to
110 maintain disconnected the opposed toothed
clutch members 45, 46 secured to or forming
parts of the cams 43, 42 respectively. If now
the cam 43 is shifted to the right, Fig. 1, to
bring said clutch members into engagement
115 the cam 42 will be clutched to and will rotate
with the shaft 39, and at the same time the
cam 43 will be disengaged from its follower
37, so that after such shift the cam 42 will
control the operation of the builder-motion
120 and the parts connected therewith.

Before describing the shifting means ref-
erence will be had to the means which is ac-
tuated during primary winding to effect the
requisite step by step operation of the wind-
ing mechanism to let off the chain 7 to effect
the gain of the traverse, whereby the ring-
125 rail rises a little higher on each successive
130

up-stroke, and descends not quite so far on each successive down-stroke. As will appear hereinafter the pick-mechanism is operated by the oscillation of the builder-arm which ever one of the cams 42, 43 is in action, but when the latter cam is acting the amplitude of oscillation of said builder-arm is so small that it is insufficient to impart the requisite letting off of the chain 7 to provide the proper gain, and accordingly I have provided means which act only during the primary winding to make up the deficiency in the gain due to the short stroke of the builder-arm. The rock-shaft 35, (to which the hook-ended arm 34 is secured) has fixedly attached to it an upturned arm 47, clearly shown in Fig. 2, to which is secured, preferably in an adjustable manner at 48, by a slot and bolt arrangement, the shank 49 of a follower 50 which coöperates with the peripheral cam portions of the traverse-cam 43. Said follower 50 is placed diagonally to the periphery of the cam, as shown in Fig. 3, in order that when the cam is shifted back to the position shown in the drawings the follower will reëngage automatically therewith, the shift of the cam to inactive position disengaging it from the follower. As each of the short peripheral cam portions of the cam 43 effects an oscillation of the builder-arm, so too, each of such cam portions will oscillate the follower 50 and the arm 47, and through the rock-shaft 35 the hook-ended arm 34 will be oscillated, and thereby the rod 30 will be reciprocated. The lever arms of the bell-crank structure 34, 35, 47 are so arranged that the length of the stroke imparted thereby to the rod 30 is sufficient to effect the proper step by step rotation of the pick-wheel 27 to give the desired gain to the traverse during the primary winding. The reciprocation thus imparted to the rod 30 is so much greater than that due to the oscillation of the builder-arm that the latter is practically inoperative, so far as regards the gain, during the primary winding.

The means for effecting the change of traverse automatically at the completion of the primary winding will now be described. The hub 51 of the traverse-cam 43 is annularly grooved at 52 to receive the yoke-like end of the shifter arm 53, the hub 54 of which is fixedly secured to a horizontal, longitudinally movable shifter-rod 55 mounted to slide in bearings provided by suitable brackets 56, 57, and parallel to the cam shaft 39. Strong shifting springs 58, 59 are coiled about the cam shaft 39 and shifter rod 55, respectively, the spring 58 being interposed between the bearing 40 and the cam-hub 51 and the spring 59 between the bearing bracket 56 and the arm 54, as clearly shown in Fig. 3, both springs being under compression during primary winding and when

free to expand acting to disengage the cam 43 from its followers 37 and 50 and to clutch the cam 42 to the shaft 39. At its inner end the shifter rod 55, extended beyond the bearing bracket 57, has rigidly attached to it a collar 60 having a frontwardly offset nose 61 and a rearwardly extended stop-lug 62, shown as rectangular in cross-section, an upturned ear 63 on the collar having fulcrumed upon it a gravity detent pawl 64, for a purpose to be referred to, and clearly shown in Figs. 4 and 5. A locking dog 65, notched at 66 to coöperate with the stop-lug 62, is pivoted at 67, Fig. 4, on the depending leg 68 of a bracket 69 bolted to and projecting rearwardly from the girder 9. When the dog is in locking position, herein shown, the upright edge of the lug 62 abuts against the opposed wall of the notch 66 and thereby the shifter rod 55 and its adjuncts are held locked against the action of the shifting springs, thus maintaining the traverse-cam 43 in action. When the said locking dog is swung upward to disengage the lug 62 the shifter rod 55 and its adjuncts are moved to the right, Figs. 1, 3 and 4, and the cam 43 is rendered inactive while the cam 42 is thrown into action, and a cam-lump 70 on the dog rides up onto the top of the lug 62 and remains there throughout the secondary winding. The coöperation of said lug and cam-lump effects a quick, sudden lift to the dog 65 when the shifter-rod is released, and thereby a trip pin 71 is brought into engagement with the detent-pawl 64 to lift it into an inoperative position. Simultaneously a second trip pin 72 on an arm 73 carried by the dog is brought into engagement with and lifts into inoperative position a feed-pawl 74.

When the shifter-rod 55 is returned to locking position the dog 65 returns by gravity to locking position and the pawls 64 and 74 become operative once more. When operative said pawls coöperate with a ratchet disk 75 rotatably mounted on a stud 76 extended frontward from the bracket leg 68, the hub of said ratchet being encircled by a spirally wound re-setting spring 77, fixed at one end against the leg 68 and at its other end attached to a pin 78 on the disk, the pin and the hub of said disk being shown in section in Fig. 4. The ratchet disk is retained on the stud 76 by the hub 79 of an angularly adjustable stop-arm 80, held in adjusted position by a set-screw 81, the arm being set to coöperate with a stop-pin 82 extended frontward from the ratchet disk. The pin 78 travels in a circular path which brings it into engagement with the locking dog 65 after the ratchet 75 has been revolved step by step by the feed-pawl 74 through a predetermined arc, regulated by the adjustment of the stop-arm 80, the more said arm is set to the right from the position shown in Fig. 1 the less the arc 130

through which said ratchet will be revolved, as will be understood. When the pin 78 engages the dog 65 it raises the notched end thereof until the lug 62 is released, but such release is not effected until the lower edge 5 of the notch 66 is elevated above the top of the lug. During this gradual rise of the dog the feed and detent pawls remain in control of the ratchet 75, as it is necessary 10 to continue the rotative movement thereof until complete disengagement of the lug 62 from the notch 66, and immediately thereafter the quick final rise of the dog is effected by the combined action of the shifting springs as the lug 62 is pushed under the cam lump 70. This rise of the dogs 15 brings the trip pins 71, 72 into action to disengage the pawls 64, 74 from the ratchet 75, and the spring 77 then operates to return the ratchet to starting position. 20 Such movements occur simultaneously with the shift or change from the primary to the secondary winding operations, as will be apparent, and the adjustment of the ratchet 25 75 at the beginning of the primary winding determines the duration of such winding. The feed-pawl 74 is pivoted at 83 to the upper end of an upturned rocker-arm 30 84 having its hub 85 mounted to rock on a horizontal stud 86 extended rearwardly from a depending hanger 87 bolted to the girder 9, Figs. 1 and 2. Said pawl-carrying arm 84 is located in the path of the nose 61 and far enough therefrom during 35 primary winding to permit the requisite oscillation of the arm, which oscillation is effected by the arm 88, Fig. 1, said arm forming a rigid part of the hub 85 and being upcurved at 89 to pass over and rest 40 upon the front end of the branch 17 of the builder-arm. As the latter rises and falls the arm 88 rises and falls with it, and the movement thus imparted to the rocker-arm 84 is sufficient to actuate the feed-pawl 74 45 properly for the step by step rotation of the ratchet 75.

The front end of the hooked arm 34 is adapted to rest upon the top of the arm 88, but during primary winding the movement 50 of said arm 88 is insufficient to give the requisite reciprocation to the pick-rod 30, hence the use of the means previously described to govern the reciprocation of such pick-rod when the primary winding of yarn 55 is being laid upon the bobbin. When the shifter-rod 55 is released at the termination of primary winding and is moved to the right, Fig. 1, the nose 61 abuts against and will swing the arm 84 in the same direction 60 a slight distance; the pawl 74 having been disengaged previously from the ratchet 75, and the arm 88 will be lifted slightly so that when the builder-arm is depressed during 65 the secondary winding the branch 17 will move away from the overhanging portion

89 of such arm at the lower end of the stroke. This is unobjectionable, however, for the stroke of the builder-arm is so much longer when controlled by the cam 42 that the arm 88 will be oscillated through an angle great enough to raise and lower the arm 34 sufficiently to effect the proper reciprocation of the pick-rod 30 for imparting the necessary gain during the secondary winding. The arm 88 has a downwardly offset prolongation 90 beyond the arched part 89, extended beneath the forward end of a foot-lever 91 having a hub pivoted at 92 on the branch 16 of the builder-arm, said lever having at its front end a foot-plate 93 within convenient reach of the operator, and at its rear end the lever is prolonged and offset to form a tail 94 which extends under the cross-brace 18, Figs. 2 and 3. Said lever is heavy enough to maintain the tail in engagement with the cross-brace under ordinary conditions, but said lever can be swung upward on its pivot when so impelled by the rise of the arm 88 when the shift is effected from short to long traverse, heretofore referred to.

When the main or secondary winding has been completed and the frame is stopped for doffing the operator places his foot upon the plate 93 and presses the lever 91 downward, to thereby depress the prolongation 90 of the arm 88. Thereby said arm is swung downward about the pivot 86 and the upright arm 84 will be swung to the left, to engage the nose 61 and push the shifter-rod 55 and its adjuncts to the left, Fig. 1, into the position therein shown, and at the same time depressing the builder-arm so that the traverse-cam 43 can readily reengage with its follower 37. Such operation places the mechanism in readiness for beginning the primary winding on a fresh set of bobbins after the frame has been doffed, the dog 65 dropping into locking engagement with the lug 62. A latch 95 is pivoted at 96 on a stand 97 bolted to the floor near the end of the frame, as herein shown, said latch having a beveled edge 98 and a locking shoulder 99, and normally the latch is positioned as shown in Fig. 2 with its edge 98 in the path of movement of the rear edge of the foot-plate 93. Such positioning may be effected in any suitable way, and herein it is effected by a weighted tail 100 forming a part of the latch, the tail acting normally to hold a stop 101 on the latch against the edge of the stand 97, Fig. 2. When the foot-plate 93 is depressed it rides over the edge 98 and pushes the latch back until the shoulder 99 thereof can swing forward and overhang the foot-plate, thereby to lock automatically the arm 88-90 in depressed position with the builder-arm at its lowest point. The attendant can then give his attention to winding back and to any other matters

which must be looked after before the frame is started up, and when everything is ready the foot-plate is depressed slightly to take the pressure off the latch and the latter is 5 swung back to release the said plate and thereby the various parts will return to position ready to begin the primary winding.

By reference to Fig. 4 it will be apparent 10 that when the dog 65 moves into position to lock the shifting mechanism for primary winding the feed and detent pawls for the ratchet 75 are simultaneously brought into coöperation therewith. If the depression of 15 the foot-plate did not effect an abnormal depression of the builder-arm there might be some difficulty in placing the cam 43 in engagement with its follower 37, but the abnormal depression of the builder-arm lowers 20 said follower entirely below the periphery of its cam, and engagement of such parts must take place when the foot-plate is released.

Various changes or modifications in 25 details of construction and arrangement may be made by those skilled in the art without departing from the spirit and scope of my invention as set forth in the claims hereunto annexed.

Having fully described my invention, what 30 I claim as new and desire to secure by Letters Patent is:

1. In apparatus of the class described, a ring-rail, an oscillating builder-arm connected with and to reciprocate the rail, primary and secondary traverse cams, separate followers for said cams, mounted on the builder-arm, the primary cam effecting a short, quick traverse of the rail, and the secondary cam effecting a longer and relatively slow traverse, a rotating cam-shaft on which the primary cam is mounted to rotate therewith, means to clutch the secondary cam to the shaft to rotate therewith, traverse-changing mechanism actuated automatically to disengage the primary cam and its follower and to render operative the said clutching means, thereby to effect active coöperation of the secondary cam with its follower, and 45 an instrumentality to coöperate with and prevent the actuation of said mechanism until the primary traverse-cam has been in action for a predetermined period.

2. In apparatus of the class described, a ring-rail, an oscillating builder-arm connected with and to reciprocate the rail, primary and secondary traverse cams to co-operate with the builder-arm, the former to effect a short, quick traverse and the latter 55 a longer, relatively slow traverse, of the ring-rail, a rotating shaft on which the cams are mounted, a permanent driving connection between the primary cam and the shaft, means to connect the latter and the secondary cam to rotate in unison, traverse-shift-

ing mechanism actuated automatically to render the primary cam inactive with respect to the builder-arm and simultaneously to effect clutching of the secondary cam to the said shaft and thereby render said cam operative to actuate the builder-arm, and an instrumentality to bring about the actuation of the shifting mechanism when the primary cam has been in action for a predetermined period.

3. In apparatus of the class described, a rotatable shaft, a bunch-building cam rotatable with and slidable axially on the shaft, a main building cam loose on the shaft, clutch members on said cams, brought into coöperation by axial movement of the bunch-building cam, spring-actuated shifting means operatively connected with and to effect such axial movement of the said cam, an instrumentality, including a locking device, to release and permit the actuation of said means at a predetermined time, a builder-arm, and separate followers thereon for said cams, the actuation of the shifting means disengaging the bunch-building cam from 90 its follower and causing oscillation of the builder-arm by coöperation of the main building cam and its follower.

4. In apparatus of the class described, a rotatable shaft, a bunch-building cam rotatable with and slidable axially on the shaft, a main building cam loose on the shaft, means governed by axial movement of the bunch-building cam to inoperative position to clutch the main building cam and the shaft, 100 a builder-arm, separate followers thereon for said cams, spring-actuated shifting means to effect axial movement of the bunch-building cam away from its follower and to clutch the other cam and the shaft, whereby said 105 latter cam is rendered operative to oscillate the builder-arm, a device to lock said shifting means from operation, and an instrumentality to cause the locking device to release the shifting means when the builder-arm has been oscillated by the bunch-building cam for a predetermined period.

5. In apparatus of the class described, a rotatable shaft, a bunch-building cam rotatable with and slidable axially on the shaft, 115 a main building cam loose on the shaft, means governed by axial movement of the bunch-building cam to inoperative position to clutch the main building cam and the shaft, a builder-arm, separate followers 120 thereon for said cams, spring-actuated shifting means to effect axial movement of the bunch-building cam away from its follower and to clutch the other cam and the shaft, whereby said latter cam is rendered operative to oscillate the builder-arm, a device to lock said shifting means from operation, and an instrumentality to cause the locking device to release the shifting means when 125 the builder-arm has been oscillated by the 130

bunch-building cam for a predetermined period, combined with manually adjustable means to vary, through said instrumentality, the length of the operating period of the bunch-building cam.

6. In apparatus of the class described, a rotatable shaft, a bunch-building cam rotatable with and slideable axially on the shaft, a main building cam loose on the shaft, means governed by axial movement of the bunch-building cam to inoperative position to clutch the main building cam and the shaft, a builder-arm, separate followers thereon for said cams, spring-actuated shifting means to effect axial movement of the bunch-building cam away from its follower and to clutch the other cam and the shaft, whereby said latter cam is rendered operative to oscillate the builder-arm, a device to lock said shifting means from operation, an instrumentality to disengage said locking device and the shifting means, including a rotatable member and an actuator to rotate it step by step, whereby the shifting means is permitted to act after said member has been rotated through a predetermined angle, and means operated by the locking device when disengaged to render the actuator inactive.

30 7. In apparatus of the class described, a rotatable shaft, a bunch-building cam rotatable with and slideable axially on the shaft, a main building cam loose on the shaft, means governed by axial movement of the bunch-building cam to inoperative position to clutch the main building cam and the shaft, a builder-arm, separate followers thereon for said cams, spring-actuated shifting means to effect axial movement of the bunch-building cam away from its follower and to clutch the other cam and the shaft, whereby said latter cam is rendered operative to oscillate the builder-arm, a device to lock said shifting means from operation, a ratchet having a projection to coöperate with and disengage the locking device from the shifting means, feed and detent pawls co-operating with the ratchet, connections between the builder-arm and the feed-pawl to operate the latter and effect step by step rotation of the ratchet, and trips on the locking device to disengage both pawls from the ratchet when the locking device is rendered inoperative.

55 8. In apparatus of the class described, a rotatable shaft, a bunch-building cam rotatable with and slideable axially on the shaft, a main building cam loose on the shaft, means governed by axial movement of the bunch-building cam to inoperative position to clutch the main building cam and the shaft, a builder-arm, separate followers thereon for said cams, spring-actuated shifting means to effect axial movement of the

bunch-building cam away from its follower and to clutch the other cam and the shaft, whereby said latter cam is rendered operative to oscillate the builder-arm, a dog to engage and lock the shifting means from operation during bunch-building, a releasing instrumentality for the dog, including a ratchet, and a feed-pawl to rotate it step by step, a rocking carrier for the pawl, actuated by oscillation of the builder-arm, and a trip on the dog to disengage the said pawl from the ratchet when the dog is moved to release the shifting means, said trip maintaining the pawl inoperative during the oscillation of the builder-arm by the main building cam.

9. In apparatus of the class described, a ring-rail, an oscillating builder-arm having a winding mechanism connected with the ring-rail, to reciprocate the latter, traverse-cams to coöperate successively with the builder-arm and through it effect, respectively, short and quick, and longer, slow traverses of the ring-rail, mechanism to render the first cam inactive and the second cam active automatically, means governed by oscillation of the builder-arm to effect gain of the traverse by or through said winding mechanism, and separate means operated by the primarily active cam to effect the requisite gain while such cam is active and the stroke of the builder-arm is too short to impart the requisite gain.

40 10. In apparatus of the class described, a ring-rail, an oscillating builder-arm having a winding mechanism connected with the ring-rail, to reciprocate the latter, traverse-cams to coöperate successively with the builder-arm and through it effect, respectively, short and quick, and longer, slow traverses of the ring-rail, automatically actuated mechanism to render the first cam inactive after a predetermined period and simultaneously to render active the second cam, a pick-motion operated by oscillation of the builder-arm to effect gain of the traverse by or through the winding mechanism, and means operated only by the primarily active cam and during the period of its activity to increase the operation of the pick-motion and thereby effect the gain of the traverse to the requisite extent.

11. In apparatus of the class described, a ring-rail, an oscillating builder-arm having a winding mechanism connected with the ring-rail, to reciprocate the latter, traverse-cams to coöperate successively with the builder-arm and through it effect, respectively, short and quick, and longer, slow traverses of the ring-rail, automatically actuated mechanism to render the first cam inactive after a predetermined period and simultaneously to render active the second cam, a pick-motion operated by oscillation

of the builder-arm to effect gain of the traverse by or through the winding mechanism, and means operating only during the period of short, quick traverse of the ring-rail to 5 increase the action of the pick-motion and thereby effect the gain of the traverse to the requisite extent.

12. In apparatus of the class described, an oscillating builder-arm having separate 10 cam-followers and a winding mechanism mounted thereon, a shiftable cam to co-operate with one follower and impart a short, rapid oscillation to the builder-arm, a second cam to co-operate with the other follower 15 and impart a longer, slower oscillation to said arm, mechanism to shift the first cam from engagement with its follower and simultaneously to throw the second cam into action, means governed by oscillation of the 20 builder-arm to actuate the winding mechanism, and other means, including a follower to co-operate with the shiftable cam, to secure to the requisite extent the actuation of said winding mechanism when said cam is 25 effecting the short and rapid oscillation of the builder-arm, whereby at such time the gain of the traverse is secured to the requisite extent, the shifting of said cam to inactive position disengaging it from the follower 30 of the gain-securing means.

13. In apparatus of the class described, an oscillating builder-arm having separate cam-followers and a winding mechanism mounted thereon, a shiftable cam to co-operate with one follower and impart a short, rapid oscillation to the builder-arm, a second cam to co-operate with the other follower and impart a longer, slower oscillation to said arm, mechanism to shift the first cam 35 from engagement with its follower and simultaneously to throw the second cam into action, means governed by oscillation of the builder-arm to actuate the winding mechanism, and other means, including a follower 40 to co-operate with the shiftable cam, to secure to the requisite extent the actuation of said winding mechanism when said cam is effecting the short and rapid oscillation of the builder-arm, whereby at such time the gain of the traverse is secured to the requisite extent, the shifting of said cam to inactive position disengaging it from the follower 45 of the gain-securing means, combined with a manually operated device to effect 50 reverse operation of the shifting mechanism and thereby cause reengagement of the shiftable cam with its follower on the builder-arm and with the follower of said gain-securing means, the second cam being 55 thrown out of action simultaneously.

14. In apparatus of the class described, an oscillating builder-arm, a ring-rail operatively connected therewith, a bunch-building cam, and a main building cam, to

effect, separately, oscillation of the builder-arm, a common rotating actuator for the cams, spring-actuated mechanism to render inactive the first, and to render active the second, of said cams, a dog to restrain said mechanism from operation, and an instrumentality to release said mechanism from the control of the dog after the bunch-building cam has been in action for a predetermined period, said instrumentality being governed by or through the oscillation of the builder-arm, combined with means, also governed by or through oscillation of the builder-arm, to impart gain to the traverse of the ring-rail, and independent means operated by the bunch-building cam when active to secure the requisite gain to the traverse during the period of bunch-building.

15. In apparatus of the class described, an oscillating builder-arm, a ring-rail operatively connected therewith, a bunch-building cam and a main building cam, to effect, separately, oscillation of the builder-arm, a common rotating actuator for the cams, spring-actuated mechanism to render inactive the first, and to render active the second, of said cams, a dog to restrain said mechanism from operation, and an instrumentality to release said mechanism from the control of the dog after the bunch-building cam has been in action for a predetermined period, said instrumentality including and being operated by a rocking arm rocked by oscillation of the builder-arm, combined with means governed by said rocking arm to impart gain to the traverse of the ring-rail, independent means operated by the bunch-building cam when active to impart the requisite gain to the traverse during such period, and a member connected rigidly with the rocking arm to restore the spring-actuated mechanism to the control of the dog by depression of the said arm to an abnormal extent.

16. A reciprocating ring-rail, and actuating means therefor, including an oscillating builder-arm, a cam to actuate it and effect a short, quick traverse of the ring-rail, and a second cam to actuate the arm and effect a longer slower traverse of the ring-rail, combined with means to throw the first cam out of action and the second cam into action when a predetermined period of short, quick traverse is completed, an instrumentality to effect gain of the traverse, and requisite gain-securing means operated by the first-named cam when it is in action, to secure the requisite gain during such period.

17. A reciprocating ring-rail, and actuating means therefor including successively-acting members to impart first a short, quick traverse and thereafter a longer, slower traverse to the ring-rail, combined with an

instrumentality operated throughout the active period of said means to effect gain of the traverse, and separate means acting only during the period of short, quick traverse to secure the requisite gain.

18. A reciprocating ring-rail, and actuating means therefor including an oscillating member and cams coöperating therewith successively to impart first a short, quick 5 traverse and thereafter a longer, slower traverse to the ring-rail, combined with mechanism to render the first cam inactive and the second cam active, an instrumentality to impart gain to the traverse, connecting 10 trolley connections between the oscillating

member and said mechanism and said instrumentality, to actuate the said mechanism at a predetermined time and to operate the said instrumentality while the oscillating member is in operation, and means to 20 secure the requisite gain during the period of short, quick traverse only.

In testimony whereof, I have signed my name to this specification, in the presence of two subscribing witnesses.

ALONZO E. RHOADES.
